UNITED STATES PATENT OFFICE.

JACOB FINK, OF PADERBORN, GERMANY.

RAIL.

SPECIFICATION forming part of Letters Patent No. 624,471, dated May 9, 1899.

Application filed October 25, 1898. Serial No. 694,553. (No model.)

To all whom it may concern:

Be it known that I, JACOB FINK, a subject of the King of Prussia, German Emperor, and a resident of Paderborn, Prussia, Germany, have invented certain new and useful Improvements in Rails, of which the following is a full, clear, and exact specification.

The present invention concerns a two-part rail for railroads, serving both as a rail and as a longitudinal sleeper or stringer. The two parts of the rail are of symmetrical shape and can be easily separated and reversed in position.

The rail is composed of two angle-irons with reinforced flanges at the outer edges, both parts being alike. The outer faces of the angles are slightly concaved centrally in order to procure tighter compression of the heads of the rails and a more uniform distribution of pressure on foot of the rail.

The new rail offers the advantage that it can be laid on the sleeper-plates of the cross-tie, and the sleeper-plates may, if found desirable, be slightly bulged. In this manner the two rail-halves will lie close to each other, with their vertical surfaces in contact, so that only the ordinary bolts are required.

In the accompanying drawings, Figure 1 shows the rail in cross-section, and Fig. 2 in ground plan on a reduced scale.

The rail consists of two symmetrical parts A and A' of the make shown in Fig. 1. The outer plane sides b' b² and b³ b⁴ are dished or concaved at 2 3 3, respectively, while the outer edges of the angle-plates have flanges a' a² a³ a⁴ of greater thickness than the intermediate portions. When two such angle-plates are laid together, as shown in Fig. 1, the parts b² b³ form the web, while the flanges a² a³ form the head of the rail, and the corresponding parts form the base or rail-foot, as at b' b⁴ a' a⁴.

The straight surfaces of the angle-irons A and A' are in close contact above and below

the concaved portions 2 3. The two angle-irons are brought into correct position upon a sleeper-plate C, which is slightly concaved or dished on its upper side between the points 5 5. The round-headed screws d serve for the fastening, said screws reaching through 50 the sleeper-plate into the cross-tie.

When laying the rail, a strip e of wood or other similar material is first pushed under the adjacent corners of the two angle-irons. Then the two angle-irons are fastened to the 55 base by means of the screws d and to each other by means of the screws c. Thereafter the strip e is removed, and the screws are tightened until the lower surfaces of the rail parts and the upper surface of the sleeper-plate 60 touch. In this manner the head and web parts of the rail are firmly pressed to each other. The joints of the two rail-halves are in such a position toward each other that the face-joints of the one rail-half are situated in 65 the middle of the opposite half of the rail.

By the present invention with a thoroughly reliable seat and coupling of the two-part rail the result is that the two angle-irons can be reciprocally interchanged. As soon as the 70 head parts a² and a³ are worn out the parts are reversed and the head parts a' and a⁴ can be used as a rail-head, and the legs, which have worn bulging, can be employed as the base or rail foot.

I claim—

A two-part railroad-rail consisting of two symmetrical and reversible angle-irons, slightly dished or concaved centrally on their level faces, combined with a slightly dished 80 or concaved sleeper-plate C and securing means, substantially as described.

In witness whereof I have hereunto set my hand in presence of two witnesses.

JACOB FINK.
